UNITED STATES PATENT OFFICE

156,696

COMB OR SIMILAR ARTICLE

Charles W. Bristol, North Attleboro, Mass., assignor, by mesne assignments, to Reibling-Lewis, Inc., Providence, R. I., a corporation of Rhode Island

Application January 14, 1948, Serial No. 143,723

Term of patent 14 years

(Cl. D86—8)

To all whom it may concern:

Be it known that I, Charles W. Bristol, a citizen of the United States of America, residing in North Attleboro, county of Bristol, State of Massachusetts, have invented a new, original, and ornamental Design for a Comb or Similar Article, of which the following is a specification, reference being had to the accompanying drawing, forming a part thereof.

Fig. 1 is a plan view, showing my new design for a comb or similar article;

Fig. 2 is an edge view thereof;

Fig. 3 is a section on line 3—3 of Fig. 1 thereof.

The dominant part of the design is shown in full lines.

I claim:

The ornamental design for a comb or similar article, as shown and described.

CHARLES W. BRISTOL.
